UNITED STATES PATENT OFFICE.

JOHN ORBIK, OF HURLEY, WISCONSIN.

DESIGN FOR A PICTURE-FRAME.

45,676.

Specification for Design.

Patented Apr. 28, 1914.

Application filed February 7, 1914. Serial No. 817,354. Term of patent 14 years.

To all whom it may concern:

Be it known that I, JOHN ORBIK, a citizen of the United States, residing at Hurley, in the county of Iron and State of Wisconsin, have invented a new, original, and ornamental Design for Picture-Frames, of which the following is a specification, reference being had to the accompanying drawing, forming a part thereof.

The figure is a plan view of a picture frame, showing my new design.

I claim:

The ornamental design for a picture frame, as shown.

JOHN ^{his} X ORBIK.
mark
